UNITED STATES PATENT OFFICE.

SINCLAIR TOUSEY, OF NEW YORK, N. Y.

FILM CARRIER.

Original application filed February 10, 1919, Serial No. 275,988. Patent No. 1,510,424, dated September 30, 1924. Divided and this application filed May 20, 1924. Serial No. 714,664.

To all whom it may concern:

Be it known that I, SINCLAIR TOUSEY, a citizen of the United States, and resident of New York, in the county and State of 5 New York, have invented certain new and useful Improvements in Film Carriers, of which the following is a specification.

This specification is a division of that belonging to application for Letters Patent 10 of the United States filed by me February 10th, 1919, Serial No. 275,988, patented Sept. 30, 1924, No. 1,510,424, in which is disclosed an X-ray film packet for use in the mouth of the patient in taking X-ray 15 pictures of diseased parts.

In the drawings—

Figure 1 is a view of one face of the film packet.

Fig. 2 is a view of the opposite face.

20 Fig. 3 is a sectional view on line 16—16 of Fig. 2.

Fig. 4 is a view of the separate insert piece.

The main body of the packet is made 25 preferably of soft annealed metal, transparent to the X-rays, and has its edge turned at a' over upon one face on all four sides. The front wall a is plain throughout and transparent to the X-rays so that 30 the field of exposure is as large as the area of this front wall. Cooperating with this front member I employ back member b consisting of a plain sheet of material having a flap or finger piece b' turned over 35 upon itself lying upon the rear face of this back member. As shown in Fig. 3 this back member is held by the overturned edge a' of the front member which also grasps the

back member along that portion where its flap or finger piece b' is located, but with 40 a considerable portion of this flap or finger piece extending from under the said overturned edge a' so that it is readily accessible to the user. In Fig. 3 c indicates the black paper and d the film or films with 45 or without X-ray proof backing. In opening this carrier the operator or the user pulls the finger piece or flap b' and this will turn the edge a' which normally overlies the flap, and thus access to the film may 50 be had.

I claim:

1. An X-ray film carrier composed of a main part having narrow edge portions turned upon itself to hold the film and another part consisting of a separate sheet of suitable substance overlying the film on that side of the first part upon which its turned edge portions are located, the said overlying part having a finger piece projecting 60 relative to said narrow edge, substantially as described.

2. An X-ray film carrier composed of a main part having narrow edge portions turned upon itself to hold the film and another part consisting of a separate sheet of suitable substance overlying the film on that side of the first part upon which its turned edge portions are located, the said overlying part having a finger piece projecting 65 relative to said narrow edge and from beneath said turned edge, substantially as described.

In testimony whereof, I affix my signature.

SINCLAIR TOUSEY.
